UNITED STATES PATENT OFFICE

2,585,662

CASTING EQUIPMENT

George C. Kohl, University Heights, Ohio, assignor to Aluminum Company of America, Pittsburgh, Pa., a corporation of Pennsylvania

Application December 17, 1948, Serial No. 65,770

2 Claims. (Cl. 22—94)

1

This invention relates in general to improvements in casting equipment and is more particularly directed to mechanism for removing or stripping cast articles from molds in which the articles have been cast.

Casting removing, stripping and/or transferring mechanisms of the type contemplated within in the scope of the invention lend themselves to association with casting equipment of the general type described and illustrated in my co-pending application for United States Letters Patent, Serial No. 178,520, filed August 9, 1950, now patent No. 2,581,418 issued January 8, 1952.

The configuration, exterior contour and distribution of metal, or other material, in any particular cast articles, are significant factors in respect to the choice of casting equipment and technique to be employed in producing castings. In the case of cup-shaped articles, such as pistons for internal combustion engines, there are certain advantages derived from casting the same in the "head-up" position. For example, the metallurgical and physical properties and characteristics of a piston benefit from the head-up casting procedure described in United States Letters Patent 2,521,520, issued September 5, 1950, in the name of Charles G. Jancura. Also, the head-up positioning of a cup-shaped casting permits the use of the internal core equipment described in my aforementioned co-pending application.

A machining or finishing operation is normally performed on castings to remove excess material in the form of gates, sprues, runners and risers. In some cases the removal of this excess material places the casting in condition for subsequent use as a finished cast product. Additional machining or finishing operations, however, may also be required in cases where an otherwise cast surface is machined to impart an entirely new configuration thereto. This latter operation may be exemplified by the machined grooves in a cast piston blank for receiving the normally used piston rings.

As an example of a cast article which combines surfaces that are machined with surfaces that remain in the as cast condition, reference is made herein to an internal combustion engine piston having an as cast exterior head surface that does not readily lend itself to machining operations to produce a desired contour in the head of the piston. Typical of the piston referred to is one in which the top exterior surface is cast in the form of an irregular, or non-symmetrical, undulating contour adapted, in

2

combination with a cylinder head, to control the progress of the flame front during ignition and burning of the fuel within the combustion chamber of an internal combustion engine.

Since the irregularly contoured piston described above does not lend itself to normal machining practices to develop its contoured head, the gating of the mold to produce the same introduces a problem in that riser, gate and sprue connections can not be made to the head of the piston, nor can any gating or metal feeding system be employed that would necessitate a machining or finishing operation on the contoured head of the piston following its solidification to an as cast surface.

Avoiding connections of the gate, sprue and or riser with the irregular as cast surface of the piston head described above has resulted in in the development of a casting mechanism that permits incorporation of a casting stripping device for removing cast articles from the molds in which they have been cast.

It is a general object of the present invention to provide improved casting equipment which incorporates positive means for grasping and conveying a cast article to a position removed from the mold in which it was cast.

It is a further object of the invention to provide casting equipment for producing pistons, having irregularly contoured heads, in a head-up position, without including a gating system that is directly connected to the irregularly contoured head.

Another object of the invention is to provide a molten metal feeding system in association with a casting mechanism that permits introduction of the molten metal into a mold cavity out of contact with an irregular and non-machinable as cast surface.

Other objects and advantages of the invention will become apparent on consideration of the following description and drawings in which:

Fig. 1 represents a fragmentary partial sectional elevation through a two-mold piston casting mechanism in which certain elements of the mechanism are illustrated in molten metal receiving relationship;

Fig. 2 represents a view similar to Fig. 1 with a portion of the mechanism in elevated position following a casting stripping operation;

Fig. 3 represents the outline of a top plan view of the mechanism of Figs. 1 and 2;

Fig. 4 represents a partial sectional elevation to enlarged scale taken in the direction of the arrows IV—IV on Fig. 1;

Fig. 5 represents a fragmentary end elevation to enlarged scale taken in the direction of the arrows V—V on Fig. 1;

Fig. 6 represents a partial plan view to enlarged scale taken in the direction of the arrows VI—VI on Fig. 1;

Fig. 7 represents a sectional plan view to enlarged scale taken along the plane VII—VII of Fig. 1;

Fig. 8 represents a sectional plan view to enlarged scale taken along the plane VIII—VIII of Fig. 1;

Fig. 9 represents a fragmentary sectional elevation to enlarged scale taken along the plane IX—IX of Fig. 8;

Fig. 10 represents a sectional plan view to enlarged scale taken along the plane X—X of Fig. 1;

Fig. 11 represents a sectional plan view to enlarged scale taken along the plane XI—XI of Fig. 1; and

Fig. 12 represents a sectional plan view to enlarged scale taken along the plane XII—XII of Fig. 4.

The invention and its mode of operation are described hereinafter in terms of equipment suitable for producing internal combustion engine pistons. It should be understood that the selection of a piston in no way limits the scope of the invention, since other cast articles may be produced by employing the equipment and practice of the invention.

Referring in general to the casting equipment of the invention, it comprises a pair of medially split molds machined, or otherwise formed, to define cooperating recesses which provide two casting cavities and inter-related gating systems for producing two pistons in head-up position. The mold sections are operatively mounted on a suitable base member and internal cores for defining the interior surfaces of the pistons are suitably supported beneath the base member. The mechanism thus far described is similar to that described and illustrated in my co-pending application, Serial No. 178,520, filed August 9, 1950, now Patent No. 2,581,418, issued January 8, 1952.

Referring to the drawings for a specific description of the invention in its application to a piston casting mechanism, right and left hand mold sections 10 and 12, respectively, are slidably mounted through the medium of keys 14 and keepers 16 on the top horizontal surface of a main base member or casting 15. Matching or similar mold sections (Fig. 7 and 11) are provided and supported on the base member 15, it being understood that each mold includes a pair of similar cooperating sections that are slidable into and out of casting cavity-forming relationship on the base 15.

A casting stripper and conveying device, represented in its entirety by the reference numeral 18, is mounted immediately above the mold members. Device 18 is preferably constructed in the form of a light metal alloy casting and is supported in cantilever relationship upon four vertical posts 20 which extend vertically upwardly from the main frame 15 of the casting mechanism. A fluid-operated cylinder 22 has its piston rod 24 secured to the underside of the frame 18 and serves to vertically reciprocate this frame from the position illustrated in Fig. 1 to that shown in Fig. 2.

Tubular columns 25 are rigidly secured, as by flange and bolt connections, to the underside of frame 18 and depend therefrom in coaxial align-

ment with each mold cavity therebelow. The tubular columns 25 are also flanged at their lower ends and are rigidly connected by suitable bolts, cap screws, or the like, to ejector pin guide plates 26. The ejector pin guide plates 26 each have a circular block or plug 28 secured to its underside, through suitable bolt connections. Plug members 28 are received within complementary openings in the top surfaces of each pair of mold sections and cooperate therewith to define the casting cavity in each of the molds. The underside of each of the plug members 28 is formed, as by a profiling operation, to define a contoured piston head in the actual apparatus herein disclosed.

Fluid-operated cylinders 30 are supported and secured upon the upper surface of frame member 18 with their piston rods 32 depending downwardly through the tubular columns 25. The cylinders 30 may be diaphragm type air cylinders. Vertically disposed ejector pins 34 and 35 are positioned within guide apertures in the plates 26. The pins 34 and 35 are secured, as by clamp nuts, at their upper ends to an annulus 36 and are surrounded by coiled springs 38, which normally exert an upward pressure against the underside of each annulus 36 to urge the same and the depending ejector pins 34 and 35 upwardly. The springs 38 are preferably encased in tubular shielding members 40, which also serve to limit the downward stroke of pistons 32 through contact with the underside of annuli 36.

Each annulus 35 is provided with aligned bifurcated depending lugs 42 on its underside between which a cross link 44 is secured, as by pin connections. The location of the annuli 36 is such that the cross links 44 pass through slots 45 (Figs. 10 and 11) machined or otherwise formed through the walls of tubular columns 25.

Frame member 18 is provided with a depending column or post member 46 at its outer end removed from the guide columns 20. The column 46 is provided at its lower end with an outwardly projecting hook or terminus 48 formed with downwardly converging side walls. A complementary cavity 50 is machined or otherwise formed in the base 15 for receiving the terminus 48. If desired, the cavity 50 may be machined or formed in a separate piece of metal or casting and attached to the left hand end of the base member 15, as best illustrated in Fig. 6. It will be observed that the complementary inclined surfaces on the terminus 48 and in the cavity 50 (Fig. 5) insure vertical registration of the frame member 18, together with its depending tubular columns 25, ejector pin guide plates 26 and contour blocks 28, with the mold cavities on the base 15. Selection and adjustment of the length of the post member 46 and engagement of the inclined walls of the terminus 48 with the complementary walls of the cavity 50 also insure positive horizontal positioning of the frame 18 and its depending elements in respect to the mold cavities on the base 15.

A positive mechanical locking mechanism is provided to insure positive assembly of the frame 18 and its depending elements in respect to the molds and base member 15, as well as to lock the frame 18 against unintended vertical reciprocation. The locking mechanism comprises a latch member 52 pivotally supported at 54 (Fig. 5) to the base member 15, or to the separate casting in which the cavity 50 has been machined. The latch 52 is pin-connected at 55 to a piston rod 56 which is reciprocally sup-

ported within a fluid-operated cylinder 58 that is oscillatably mounted on the main frame 15, as by pivotal connection thereto at 60. It will be understood that manipulation of pressure to the cylinder 58 will serve to reciprocate the rod 56 and oscillate latch 52 from its broken line position, out of engagement with the hook 48, into its full line locking position (Fig. 5), in which the latter position the casting stripper device 18 is vertically immovable. As an aid in supporting the overhanging portion of the casting stripper device 18, rod members 62 are provided, these rods being secured to the frame 18 adjacent the columns 20, closest to the main frame 15, and also secured to the outer or overhanging end of the device 18 adjacent the column support 46.

The gating and molten metal feeding system for the apparatus thus far described is best illustrated in Figs. 1, 2, 4, 7 and 11. Portions of the gating system are identical to that described and claimed in United States Letters Patent 2,521,520, issued September 5, 1950, in the name of Charles G. Jancura. Since the type of casting to be produced in accordance with the equipment of the present invention does not permit employing a central riser attached to the contoured piston head, and since a riser is essential to insure correct filling of the casting cavity in each mold, as well as to insure correct physical and metallurgical properties in the final object being cast, the gating system in the present equipment has been modified over that disclosed and claimed in the aforementioned Jancura patent.

The gating system for each mold incorporated in the present apparatus, comprises an entrance gate 64 which is preferably downwardly and inwardly inclined into communication with an elbow 65 (Fig. 2) that is slightly below the level of the top surface of the piston defining cavity. The elbow discharges downwardly through a runner or sprue 66 and enters the piston cavity through a ring gate 67 preferably surrounding and in communication with the bottom skirt portion of the piston cavity. The elbow 65 is also connected to an upwardly inclined sprue or runner 68 which communicates with an arcuate sprue or runner 70 (Figs. 2 and 7), the extreme outer ends of which communicate with riser cavities 72. The rise cavities 72 (Figs. 2, 4, 7 and 11) are preferably two in number and are located one on each side of a mold cavity, adjacent the top thereof, and communicate with the mold cavity through a gate 74 (Fig. 4), located below the top surface of the piston being cast, over an arcuate length at least equal to the arcuate length of each of the risers 72 at the plane of communication between the risers and each mold cavity.

Riser cavities 72 are formed by removing metal, or the material from which the molds 10 and 12 are constructed, as by a machining operation, and the cavities thus formed co-operate with the peripherally sloped side wall of each plug member 28 to provide a downwardly converging draft (Figs. 2 and 4) toward the head or top surface of each piston, the purpose of which will be explained hereinafter. If desired, a single annular riser cavity, surrounding each central plug member 28, may be substituted for the separated riser cavities 72.

The mold sections 10 and 12, there being an identical pair of each of the sections medially split on a central plane for slidable separation

to expose a finished casting, as previously described, are preferably constructed with removable plates 75 and 76 bolted or otherwise secured to the top surfaces of the mold sections 10 and 12, respectively. It is within the plates 75 and 76 that the riser cavities 72 are formed or machined, and the piston cavity and gating system for each mold are also preferably machined, the actual construction following that described in my co-pending application, Serial No. 178,520, filed August 9, 1950.

Further details of construction include the manner in which the tubular flanged columns 25 are attached to the top plug members 28. On reference to Figs. 4, 7, 8 and 9, it will be found that the lower flanged ends of tubular columns 25 are aligned with disc or plate members 26 by means of dowel pins 78 and the plates 26 are secured to the column flanges by bolts 80. The dowel pins 78 extend downwardly through the plates 26 into the plug members 28, which latter members are also secured in assembled relationship by means of bolts 82.

The mold sections 10 and 12 are preferably constructed from cast iron and may be cooled by passing coolant through internal passages provided therein but not shown. It is also preferred to cool the plug members 28 in that these members are in contact with the highest temperature metal introduced into the mold cavities. For this purpose coolant, such as compressed air or liquid coolant is introduced through delivery pipes 84, manifold 85 and tubing 86 into cavities 88 (Fig. 9) in the interior of plug members 28, the coolant, in the case of compressed air, being expelled to atmosphere through the vents or ducts 90 in the flanges secured, as by welding, to the lower ends of tubular columns 25 (Figs. 9 and 11). Where liquid coolant is employed, ducts 90 would be connected through flexible hose with a suitable discharge sump.

The molds are also suitably vented by constructing the plug members 28 in at least two parts in which case segments 92 are secured by cross bolts 94 to provide gas passages 95 from the mold cavities to atmosphere (Figs. 8 and 9).

In the operation of the casting equipment of the invention, molten metal is simultaneously introduced into the gates 64, which may be provided with annular dams 96 welded or otherwise secured to the top surface of mold sections 10 and 12. The mold cavities fill from their bottoms upwardly to at least the level of the elbows 65, after which uninterrupted feeding of molten metal through the gates 64 is directed through sprues 68 and arcuate runners 70 into risers 72 which discharge into the mold cavities through the gates 74 at the top of the molds to complete the mold filling operation and provide a hot molten metal reserve in the risers.

On solidification of the castings (pistons in the illustrations), the mold halves are separated and the internal cores (not shown) withdrawn in accordance with the practice described in my co-pending application, Serial No. 178,520. To insure against downward movement of the exposed casting, insert blocks 98 (Figs. 4 and 12) embrace and support the underside of the ring gate solidified metal at the lower end of the pistons 100.

Separation of the mold sections and removal of the internal core members, exposes the cast pistons 100, together with the attached solidified gate metal, sprues, runners and risers, clamped

between the lower blocks 98 and upper plugs 28. The plug members 28 through their downwardly tapering peripheries, frictionally engage the inner arcuate surfaces of risers 72 and afford sufficient frictional engagement to permit the pistons being raised vertically through upward vertical movement of the casting stripper frame 18. With frame 18 in its raised position, as illustrated in Fig. 2, the pistons depending therefrom are released or discharged through manipulation of cylinders 30. Pressure admitted to cylinders 30 lowers piston rods 32, the lower ends of which strike cross links 44 depressing the same together with annuli 36 and ejector pins 34 and 35 against the upward resilient pressure of springs 38. The lower ends of the ejector pins in their raised position (Figs. 2 and 9) engage solidified sprue metal at 102 and integral cast projections 104 extending outwardly from the cylindrical head portions of the pistons. It will be appreciated that ejector pins 34 may be located within the area of the top of the pistons and engage the pistons instead of the integral projections 104. Reciprocation of the ejector pins 34 and 35 will exert a downward pressure on the cast pistons with sufficient force to overcome the restraining frictional engagement between plug members 28 and riser metal 72, thereby discharging the pistons. A suitable chute, or the like, may be reciprocated under the depending pistons in the manner described in my co-pending application, Serial No. 178,520, filed August 9, 1950.

The cast pistons in practice, are machined, or otherwise rough finished, to remove the excess gate, sprue, runner, and/or riser metal cast integral therewith. It will be observed that no machining is required over the surfaces defining the contoured heads of the pistons, all excess metal removing operations being confined to surfaces that submit to normal machining operations, such as lathe cutting and grinding operations.

The mechanism may be manually or power operated. For example, the introduction of fluid pressure to cylinders 22, 30 and 58 may be controlled in proper sequence and duration in accordance with the system described in my aforementioned co-pending application.

What is claimed is:

1. A casting mechanism comprising a mold provided with a cavity partially defining both the exterior surface of a finished casting and a riser attached thereto, a plug member reciprocally supported above said mold in alignment with said cavity, said plug member being reciprocable into said cavity to a position therein to further define the exterior surface of the finished cast-

ing and a wall of the riser, said riser wall defining surface of the plug member being tapered toward the finished casting and in frictional engagement with said riser on solidification of casting material within the cavity, and ejector member mounted on said plug member and extending through the same into contact with the finished casting, a lost-motion connection between the ejector and plug members, means for reciprocating the plug member, ejector and frictionally engaged riser and attached finished casting upwardly away from said mold, and means for reciprocating the ejector member relative to said plug member to release frictional engagement of the riser and eject a finished casting and attached riser.

2. In a casting mechanism comprising a mold provided with a cavity partially defining both a finished casting and a riser integrally connected thereto, a finished casting transfer and stripping device including a plug member reciprocally mounted in coaxial alignment with the cavity, said plug member extending into said cavity to a position therein to further define an exterior surface of the finished casting and complete the riser, said plug member having a riser wall-defining surface tapered inwardly toward the finished casting in the zone of connection between finished casting and riser, and said tapered riser wall establishing frictional engagement between the plug member and riser on solidification of casting material within the cavity, an ejector supported on said plug member, said ejector having lost-motion connection with the plug member and establishing resilient engagement with a finished casting, means for reciprocating the plug member, ejector and frictionally engaged riser and finished casting to transfer the same to a new location away from the mold, and means for reciprocating the ejector relative to the plug member to strip the finished casting and connected riser from the plug member.
